UNITED STATES PATENT OFFICE.

ALFRED FREEBERG AND CARL E. DOMBROWSKI, OF NORWICH, CONNECTICUT.

SELF-CLOSING VALVE.

Application filed December 3, 1921. Serial No. 519,673.

To all whom it may concern:

Be it known that we, ALFRED FREEBERG and CARL E. DOMBROWSKI, citizens of the United States, residing at Norwich, in the 5 county of New London and State of Connecticut, have invented certain new and useful Improvements in Self-Closing Valves, of which the following is a specification.

The present invention relates to self-closing valves constructed so as to be especially useful in flushing tanks and the like and has for its principal object to provide a valve of this nature which when once opened will automatically return slowly to a closed 15 position allowing sufficient liquid to pass therethrough during its closing movement for flushing purposes.

Another important object of the invention is to provide means whereby the speed 20 at which the valve will close after having been opened may be regulated.

Another object of the invention is to provide means for opening the valve which when released will automatically return to 25 an inoperative position so as to not interfere with the automatic closing of the valve.

A still further object of the invention is to generally improve upon valves of this character by providing a device which will 30 be of extremely simple, durable and inexpensive construction, one which is efficient and reliable in operation, and well adapted to the purpose for which it is designed.

With these and numerous other objects in 35 view, the invention resides in certain novel features of construction, and the combination and arrangement of parts as will be hereinafter fully described and claimed.

In the drawing:

40 Figure 1 is a vertical longitudinal section taken through the valve.

Figure 2 is a transverse section taken on the line 2—2 of Figure 1 looking in the direction of the arrow,

45 Figure 3 is a transverse section taken on the line 3—3 of Figure 1 looking in the direction of the arrow.

Figure 4 is a detailed elevation of the auxiliary valve member,

50 Figure 5 is a transverse section taken therethrough on the line 5—5 of Figure 4 looking in the direction of the arrow, and

Figure 6 is a similar view taken on the line 6—6 of Figure 4 looking in the direction of the arrow.

55 Referring to the drawing in detail it will

be seen that 1 designates the shell of the valve which is provided with an inlet chamber 2' preferably having threads therein so that it may be connected to a supply pipe, a valve chamber 2, and an outlet chamber 3 which is provided with threads so that it may be connected to a pipe leading to a tank or some other like device, when the valve is to be used for flushing purposes.

60 An opening 4 communicates the chambers 2 and 2' and an opening 5 comprising a valve seat communicates the chambers 2 and 3. In the wall of the shell 1 there is provided a channel 6 which runs longitudinally with the chamber 2 and communicates therewith at its top through the aperture 7 and at its bottom through the aperture 8. A screw member 9 is disposed intermediate the ends of the channel 6 so as to extend transversely thereof whereby the flow of water through the channel may be regulated. It

70 is to be understood that the interior width of the channel is equal to the thickness of the screw. The head of the screw 9 is situated in a boxing 10 closed by the cap 12. A box-like valve 13 is movably mounted in the valve chamber 2 and has an opening 14 in its lower end for movably receiving the auxiliary valve member 15. Another opening is provided in its upper end and suitable 75 packing retaining means 17 is situated therein for supporting the packing 18. A rod 19 is situated transversely of this upper opening across the packing retaining means 17 so as to limit the movement of the auxiliary valve 15.

80 By referring particularly to Figures 4, 5 and 6 it will be seen that the auxiliary valve 15 comprises a disk 16' which is adapted to engage the valve seat 20 at the upper end of the opening 14, thereby closing the opening 14. A stem 21 depends from the disk 16' and has a plurality of grooves 22 therein so as to allow the escape of the water or other 85 liquid when the disk 16' is raised from its seat 20.

90 A spindle 23 is journalled transversely of the outlet chamber 3 and is provided intermediate its ends with a cam member 24 95 adapted to engage the valve stem 21 so as to raise the auxiliary valve 15. This spindle, however, is normally held in an inoperative position by the spring 25 which forces the cam constructed end 26 in engagement 100 with the cam block 27 so that when the spindle is turned the spring will be com-

105

110

pressed and when the spindle is released this spring and the cam end 26 and cam block 27 will cause the spindle to return to its original position.

- 5 To operate the valve the spindle 23 is oscillated thereby causing the cam 24 to engage the auxiliary valve 15, that is its stem 21 and lift it from off the valve seat 20. As the spindle is further rotated the cam 10 causes the auxiliary valve 15 to abut the rod 19 and thus lift the box-like valve off of its seat 5 and the water is, therefore, allowed to flow freely from the inlet chamber 2', through the valve chamber 2, and out 15 through the outlet chamber 3. In the meanwhile the water flows through the opening 8, through the channel 6, and through the opening 7, to the upper portion of the valve chamber 2 tending to fill the box like valve. 20 When the cam 24 of the spindle is disengaged from the stem of the auxiliary valve this auxiliary valve will close and the water will fill the box-like valve and the portions of the valve chamber thereabout and 25 the weight of the water will become sufficient to overcome the pressure working upwardly on the box-like valve and thus the box-like valve will come to a closed position. The speed at which this box-like valve 30 will close is regulated by the set screw 9 which allows or regulates the water flowing through the channel 6.

While the preferred embodiment of our valve has been described in detail, it will be understood that we do not wish to be limited to the particular construction set forth, since various changes in the form, proportions, and arrangement of parts, and in the details of construction may be resorted to without departing from the spirit and scope of the invention, or destroying any of the advantages contained in the same, heretofore described and defined in the subjoined claims.

45 Having thus described our invention what we claim as new is:

1. A valve comprising a main body portion, an inlet, an outlet, a channel formed on the side of the body communicating its upper and lower extremities with the interior of the body, and a valve seat formed adjacent the outlet; a main valve slidably mounted in the body comprising a casing having a comparatively large opening formed in the upper extremity and a tubular passage formed in the lower extremity thereof, a flanged ring mounted in the upper extremity of the casing, a rod positioned diametrically across the said flanged ring, a valve seat formed on the upper edge of the tubular passage, packing means adapted to permit the main valve to tightly seat upon the seat formed in the main body; an auxiliary valve slidably mounted in the tubular passage formed in the main valve compris-

ing a valve stem adapted to snugly fit the said tubular passage, a disc formed on the upper extremity thereof having packing means adapted to engage the seat formed on the tubular passage, and a ring on the lower extremity for operating the same; and an operating spindle rotatably mounted in the valve outlet comprising a cam body mounted centrally of the outlet and means for readily actuating the said cam body.

2. A valve comprising a main body, an inlet chamber, an outlet chamber, a channel formed on the side of the body communicating at its upper and lower extremities with the interior of the body, means for controlling the passage of matter through the said channel, and a main valve seat formed adjacent the outlet chamber; a main valve slidably mounted in the body comprising a main casing having a comparatively large opening formed on the upper extremity and a tubular passage formed on the lower extremity thereof, a flanged ring mounted on the upper extremity of the casing, a rod mounted diametrically across the flanged ring, an auxiliary valve seat formed on the upper edge of the tubular passage, and means for tightly fitting the said main valve upon the main valve seat; an auxiliary valve adapted to engage the seat formed on the tubular passage; and a ring formed on the lower extremity of the valve by which the same is actuated; and operating means consisting of a cross shaped cam member positioned transversely across the outlet chamber, a stem for rotating the same and raising the auxiliary and main valve members in the order named.

3. A valve comprising a body having an inlet and an outlet formed thereon, a channel communicating with the body formed on one side thereof, and a valve seat formed adjacent the outlet; a main valve slidably mounted in the body including a tubular sleeve formed at the lower extremity thereof, and a rod secured across the upper extremity; an auxiliary valve including a stem adapted to reciprocate within the tubular sleeve, a disc formed on the upper extremity of the said stem adapted to seat upon the upper edge of the said tubular sleeve; and an operating spindle rotatably mounted in the lower portion of the valve including a cam shaped body adapted to engage the lower portion of the auxiliary valve stem, and means for operating the said cam body.

4. A valve comprising a body having an inlet and outlet formed thereon, a channel formed on the side of the body communicating therewith, means for controlling the passage of matter through the said channel and a valve seat formed in the lower portion of the said body; a main valve slidably mounted in the said body including a tubu-

lar sleeve formed in the lower portion thereof; a rod secured transversely across the upper extremity of the said valve, and means for permitting the said valve to 5 tightly engage the valve seat formed in the body; an auxiliary valve including a stem adapted to move vertically within the said tubular sleeve, a disc formed on the upper extremity of the said stem adapted to engage the upper edge of the tubular sleeve to form a valve stem, a cam shaped operating member rotatably mounted at the lower

portion of the body adapted to engage the lower extremity of the said valve stem for operating the same, and means for actuating the said cam shaped member. 15

In testimony whereof we affix our signatures in presence of two witnesses.
